SLIDING DOOR CHAIN GUARD

Louis G. Bobrowski, Berlin, Conn., assignor to The Stanley Works, New Britain, Conn.

Filed Sept. 8, 1971, Ser. No. 178,853

Term of patent 14 years

Int. Cl. D8—07

U.S. Cl. D8—131

FIG. 2

FIG. 4

FIG. 3

FIG. 1 is a front elevational view of a sliding door chain guard showing my design;

FIG. 2 is a top plan view;

FIG. 3 is a bottom plan view;

FIG. 4 is a left side elevational view; and

FIG. 5 is a right side elevational view.

I claim:

The ornamental design for a sliding door chain guard,
as shown.
